Primary Examiner — Susan Bennett Hattan*Assistant Examiner* — Jennifer Wright(74) *Attorney, Agent, or Firm* — Chun-Ming Shih; HDLS IPR Services(57) **CLAIM**

The ornamental design for a lens, as shown and described.

DESCRIPTION

FIG. 1 is a perspective view of a lens showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is second perspective view showing the lens; and,

FIG. 9 is a cross sectional view taken along line 9-9 shown in FIG. 6.

1 Claim, 9 Drawing Sheets---
